UNITED STATES PATENT OFFICE.

LILLIAN H. WINEMAN, OF DEVILS LAKE, NORTH DAKOTA.

DUPLEX PENHOLDER.

1,303,442.

Specification of Letters Patent. Patented May 13, 1919.

Application filed February 11, 1919. Serial No. 276,419.

To all whom it may concern:

Be it known that I, LILLIAN H. WINEMAN, a citizen of the United States, residing at Devils Lake, in the county of Ramsey and 5 State of North Dakota, have invented certain new and useful Improvements in Duplex Penholders, of which the following is a specification.

The object of my invention is the provision of a penholder having improved carriers adapted for holding two pens, independently of each other, permitting the use of one pen or the other at will, according to the requirements of the user. With my 10 penholder, the respective pens may be used for differently colored inks, for instance red and black, or, two different kinds of pens may be held by the respective pen-carriers and one or the other used, according to the 15 nature of the pen-work to be done.

The invention comprises two, independently slidable, pen carriers arranged to be projected, or retracted, at will and which are constructed, mounted, and related in an 20 improved manner. The pen carriers are combined in a novel manner with a shell into which the pens may be singly, or collectively, withdrawn, thus guarding the pens from injury when neither is in use and housing 25 one pen when the other is in use. Preferably, there is a central member, within the shell, against which the carriers slide.

The invention is set forth hereinafter and its novel features and combinations are 30 cited in the appended claims.

In the accompanying drawings:

Figure 1, is a side elevation, one of the pens being projected, with its button in position to be turned to lock its carrier;

40 Fig. 2, is a longitudinal section, the central member and penholder stem being in full lines;

Fig. 3, is a detail cross-section on line 3—3, Fig. 2;

45 Fig. 4, is a detail side view of the shell; and

Fig. 5, is a detail view of one of the pen-carriers and its button.

The stem of the penholder is shown at 1 50 and the shell to which the pen-carriers are attached, appears at 2. Preferably, the stem is continued as, or is provided with, a member 3 which extends centrally and longitudinally within the shell. The shell 2 and member 3 is cylindrical. The shell 2 may

be secured to the stem 1 in any desired manner.

The shell is provided with two longitudinal slots 4, 5, each having a transverse, locking extension 6 at its outermost end. The 60 slots may have similar locking extensions at their innermost ends, if desired.

The pen carriers 7 and 8 are arc-shaped in cross-section and constructed to hold the pens 9 and 10 in any suitable manner, permitting their removal, when new, or other, 65 pens are desired to be substituted.

The carriers preferably conform to the inner surface of the shell 2 and to the outer surface of the central member 3 and are mounted to slide snugly, yet easily, between the said shell and member. The carriers are provided with buttons 11 and 12 secured thereto in any suitable manner, whose shanks fit, and are slidable in the slots 4, 70 5, and may be turned to enter the extensions 6, to lock the carrier when the pen is projected. The cylindrical form of the member 3 and the arc shape of the carriers 7 and 8, enables the latter to turn about the member 3, as well as slide thereon. The member 75 3 thus holds the carriers firmly at all times without interfering with their sliding or turning functions.

The buttons 11 and 12 may be colored, as 80 black and red, or provided with any other indicia, to indicate the ink to be used with the particular pen, or, to show the nature 85 of the pen.

Both pens may be withdrawn into the shell 2 and thus protected when not in use. Either pen may be projected and locked by sliding its button and turning the button into the transverse extension 6, as shown in Fig. 2.

90 The carriers 7, 8 being snugly, yet slidably, fitted in between the shell 2 and the member 3, they are held firmly and all looseness is prevented.

95 Modifications may be resorted to within the spirit of the invention.

What I claim is:

1. In a duplex penholder, the combination with a shell having longitudinal slots each provided with a transverse branch, of 100 arc-shaped pen-carriers, each provided with a button whose shank is movable in one of said slots and adapted to be turned into the transverse branch thereof to lock said carrier, said carriers serving for withdrawal of

the pens into the shell or their projection therefrom, and a member extending longitudinally within the shell between the carriers and provided with curved surfaces on which the carriers slide and turn.

2. In a duplex penholder, the combination with a shell having longitudinal slots each provided with a transverse branch, of arc-shaped pen carriers, each provided with 10 a button whose shank is movable in one of said slots and adapted to be turned into the transverse branch thereof to lock said

carriers, said carriers serving for withdrawal of the pens into the shell or their projection therefrom, independently of each 15 other, and a cylindrical member extending longitudinally within the shell between the carriers, said arc shaped carriers being slideable on said cylindrical member and adapted to turn thereon when the shanks of the 20 buttons are turned into the transverse branches of the slots.

In testimony whereof I affix my signature.
LILLIAN H. WINEMAN.
